UNITED STATES PATENT OFFICE.

HAAKON A. MARTIN, OF DAYTON, OHIO, ASSIGNOR TO THE NATIONAL CASH REGISTER COMPANY, OF DAYTON, OHIO, A CORPORATION OF OHIO, (INCORPORATED IN 1906.)

INDICATOR MECHANISM FOR CASH-REGISTERS.

1,208,810.

Specification of Letters Patent. Patented Dec. 19, 1916.

Application filed May 15, 1914. Serial No. 838,730.

To all whom it may concern:

Be it known that I, HAAKON A. MARTIN, a citizen of the United States, residing at Dayton, in the county of Montgomery and 5 State of Ohio, have invented certain new and useful Improvements in Indicator Mechanism for Cash-Registers, of which I declare the following to be a full, clear, and exact description.

10 This invention relates to accounting machines and the like, and more particularly to the indicating mechanism thereof.

The principal object of this invention is to provide an improved rotary indicating 15 mechanism so that the digits or characters to be displayed may be made larger than those on the ordinary forms of rotary indicators, without the necessity of making the drums or rollers larger in diameter.

20 The principal objection to the ordinary form of roller or drum indicators heretofore known is, that because of the limited surface available on the peripheries, unless the indicators are made unreasonably large in diameter, the characters or digits for a bank or 25 denominational section of the machine are smaller than desired. This objection has been overcome by providing an indicator comprising two members for each denomina-

30 nation, one member being mounted within the other. Part of the digits of one denomination are arranged on the periphery of one member which bears the remaining digits 35

has but a partial periphery or flange formed concentric to said drum, which second member will be hereinafter referred to as the partial drum. By distributing the characters or digits on two members, instead of 40 one, the indication is made clearer, and at the same time, because one member, the drum, is within the other, more space in the machine for the indicating mechanism is not required.

45 With these and incidental objects in view, the invention consists in certain novel features of construction and combination of parts, the essential elements of which are set forth in appended claims, and a preferred form of embodiment of which is hereinafter described with reference to the drawings which accompany and form part of the specification.

Of said drawings: Figure 1 is a transverse 55 vertical section taken through a machine,

having the present invention applied thereto. Fig. 2, is the detail front view of the improved indicating mechanism, the dollars and tens-of-dollars indicating members being shown in cross section to expose their construction and arrangement more clearly to view. Fig. 3 is a detail side view of one of the partial indicating drums, bearing the digits of higher value, and also shows an actuating segment gear for the partial drum 60 in the zero position. Fig. 4 is a detail in left elevation of one of the differential elements and some of its connections. Fig. 5 is a top plan view of the mechanism shown in Fig. 4 and in addition to this shows the relationship of the controlling keys to said mechanism. Fig. 6 illustrates the positions assumed by the various parts of the key bank and differential mechanism when a key is depressed and the machine operated far 65 enough to disconnect the differential arm from its driving device.

Described in general terms, the invention in the preferred form disclosed herein comprises, as stated above, two indicator members for each denomination, each member bearing a part of the series of digits 0 to 9. One of these members is of the ordinary construction, except that the digits 0 to 6 inclusive, instead of the digits 0 to 9, are equidistantly arranged about its peripheral flange or cylindrical surface. This drum, which will be called herein the inside or complete drum for convenience, is positioned to rotate within another member having a peripheral flange or surface just sufficiently long to bear the digits 7, 8 and 9. The preferred arrangement of the digits, as shown in the drawings, is for illustrative purposes only, as it is evident that the series 80 of digits may be differently distributed over the peripheries of the two members, if it is so desired. The actuators for the two members are rigidly connected together and operated by a common differential mechanism. 85 The actuators are so constructed that the partial drum either remains in or is moved to its non-indicating position when one of the digits on the inside drum is to be displayed. When the partial drum is moved to display one of its digits, the inside drum is also rotated, but as the peripheral flange of the partial drum moves before the sight opening in the cabinet of the machine, it conceals the digits on the inside drum. 90 95 100 105 110

In the accompanying drawings the invention is shown applied to a machine having key controlled differential mechanism substantially the same as is fully shown and described in a co-pending application No. 718,065 filed in the United States Patent Office on August 31, 1912 by H. A. Martin, the present applicant. This differential mechanism has been shown in the present application as an illustration of one form of differential mechanism with which the improved indicating mechanism of the present invention may be used, and it is not intended to limit this invention to use with this particular differential mechanism. The above mentioned application may be referred to for a detailed description of the differential mechanism and the keyboard, shown in the present application, it being considered necessary only to describe these parts generally here.

As usual there are nine amount keys 1 in a bank for each denomination represented in the machine. These keys are slidably mounted in ways cut in a supporting frame 2 supported by two cross rods 3. The keys are provided with pins 5, normally in position to engage the upper ends of slots 6, adjacent the pins, and formed in a plate 7. The plate for each bank is pivotally supported on two arms 8, which are pivotally mounted at 9 to the key frame, so that when a key is depressed its pin 5 will pass in the corresponding slot 6 and move the plate 7 upward. The lower end of the plate 7 is connected by link 11 to the outer end of an arm 12 (Fig. 4) pivotally attached at 13 to the side of a plate 4 which is integral with the key frame 2. Rigid with this arm 12 is a zero stop pawl 14, provided with a projection 15, which normally projects into the path of a shoulder 16 on a pawl 17 formed with a hook 18. The raising of the plate 7 upon depression of a key, through the link 11 and arm 12, rocks the pawl 14 to move its projection 15 out of the path of movement of the shoulder 16.

Detent means for locking the keys in depressed positions are not shown in the drawings, as any one of the well known forms of mechanisms performing this function may be employed. It is also to be understood that the usual springs, coiled about the shanks of the keys, but not shown in the drawings, are employed to restore operated keys to undepressed positions when released.

The pawl 17 is pivotally mounted at 19 on a differentially movable arm 20 loosely mounted upon a stud 21 projecting laterally from the plate 4. The forward hooked portion 18 of the pawl 17 is normally held in front of a roller 22 by a spring 23, connecting the pawl and the arm 20. The roller 22 projects from a link 24 and normally

rests in a recess 25 formed in the forward end of the differentially movable arm 20 and is normally prevented from moving out of said recess by the hook 18. The link 24, at its rear end, is pivoted by a pin 26 to an arm 27 loosely mounted on the stud 21. Each of these arms 27, there being one arm for each of the arms 20, is pivotally connected at 28 to a corresponding link 29, through the lower end of which passes a tie bar 30. The tie bar 30 is supported by the forward ends of two arms 31 mounted to rock on a cross rod 32. Each arm 31 carries a roller 33, which projects into a groove 34 formed in a corresponding disk 35, rigidly mounted on a shaft 36, there being two of said disks 35. The shaft 36 is given one complete rotation at each operation of the machine in the direction of the arrow by means of a crank handle or other suitable means, not shown in the drawings. The cam grooves 34 in the two disks 35 are so designed that during one complete rotation of the shaft 36 the arms 31 and, through the links 29, the arms 27 will be oscillated first in a counter clockwise direction, and then in a clockwise direction to normal position. This movement will be transmitted to the arm 20 through the medium of the link 24 so long as the hook 18 remains in the path of roller 22 thereby maintaining a rigid connection between arms 20 and 27. When the arm 20 is so moved, the shoulder 16 of the pawl 17 clears the ends of the undepressed keys in its bank, but engages and is arrested by the end of any key which has been depressed. This engagement moves the pawl 17 away from in front of the roller 22, thus freeing this roller for movement away from the stud 21, and permitting the roller to ride outward into the corresponding one of grooves 38 properly positioned in the key frame for this purpose. The positions of the parts at this point in the operation are as shown in Fig. 6. In this manner, the differentially movable arm 20 is arrested by the key depressed, further movement of the arm 27 causing only the idle movement of the link 24 and arm 27 as a toggle without further driving the arm 20. During the return movement of the arm 27, the roller 22 is again moved into the notch 25 in the arm 20, and the latter is returned to normal position with the arm 27. It can be seen that the zero stop pawl 14 is provided so that, if no amount key is depressed, the arm will be arrested in its zero position, the roller 22 being forced into the zero groove 39.

A link 41 is pivoted at 42 to an arm 43, which is rigidly secured to the side of the differentially movable arm 20. The rear end of the link 41 is pivotally connected to the lower end of a link 45 which, at its opposite end, is pivoted to a rearwardly ex-

tending arm 46 of an actuating segment gear 47 loosely mounted on a cross rod 48. The link 41 is curved intermediate its end to fit around the stud 21. When the indicating mechanism of a denomination is to be moved from a lower to a higher indicating position, the link 41 engages a collar 411 on the stud 21 and moves the segment gear 47 rearward for this purpose. When the indicating mechanism, however, is to be moved from a higher to a lower indicating position, movement of the arm 20 does not carry the link 41 against the collar 411. A roller 50 on the link 29 is provided for this purpose, as the roller during the raising of the link 29 moves the link 41 against the collar 411, and thereby moves the segment gear 47 forward to move the indicating mechanism to the desired lower indicating position. The roller 50, of course, engages the link 41 at every operation and remains in engagement until after the indicator drums are aligned in their set positions as will be described later.

The indicating mechanism for each denomination comprises the two members 51 and 52. The drum 51 is of the ordinary construction, and has digits 0 to 6 inclusive, arranged equi-distantly on its peripheral flanged portion 53 which forms a complete cylindrical surface. The partial or outside drum 52 has a peripheral flanged portion 54 which is just long enough to bear the three digits 7, 8 and 9, which are preferably of the same size as the digits on the complete or inside drum 51. The peripheral portions of the two members are concentric, the peripheral portion 54 of the partial drum being constructed to project over and in the opposite direction from that of the drum 51. It can, therefore, be seen that the drum 51 is mounted to rotate within the partial drum 52, the digits on one section or the other being viewed through the sight opening 56 (Fig. 1) in the front of the cabinet 55 of the machine, and the sight opening 57 in a plate 58 extending across the front of the indicators fastened to the cabinet of the machine and so constructed that only one digit at a time can be viewed.

As best shown in Fig. 1, the drum 51 is rigidly connected by pins 59 to a pinion 60 loosely mounted on a cross rod 61 extending across the machine. The partial or outside drum 52 is connected in a like manner to a pinion 62, Fig. 2, also loosely mounted on the cross rod 61. The pinions 60 and 62 respectively have oppositely extending hubs 63 and 64, and these hubs, together with the small spacing sleeves 65 inserted between the pinions 60 and the pinions 62 for the partial drums of next higher order serve to prevent movement of the drums longitudinally of the cross rod 61. The actuating segment gear 47 meshes with the pinion 60, which

has seven complete teeth (Fig. 1). A segment gear 66 (Fig. 3) which has three teeth 67 formed on its forward end is adapted to mesh with and rotate the pinion 62 rigid with the partial drum. The segment gear 66, as well as the segment gear 47, is loosely mounted on the cross rod 48 and the two segment gears are rigidly connected together by a sleeve 70 encircling the cross rod 48. One tooth of the pinion 62 is cut away at 68 to form a curved locking surface, which is adapted to co-operate with the curved edge or periphery 69 of the segment gear 66, and thereby lock the partial drum against rotation, except when the segment 66 is moved so that its teeth 67 mesh with the complete teeth of the pinion 62. The gear ratio between the segments and gears is such that seven steps of movement of segments 47 will effect one complete rotation of pinions 60 and drums 51.

From the above description it can be seen that, when the seven rearmost teeth of the actuating segment gear 47 are giving the inside drum 51 one complete rotation the circular edge 69 of the segment gear 66 will be in sliding engagement with the locking portion 68 of the pinion 62 to lock the partial or outside drum against movement. During this movement of the inside drum, without movement of the outside drum, the digits on the former can be seen through the sight openings 56 and 57. After the segment gears 47 and 66 have been moved forward sufficiently to carry the teeth 67 of the segment gear 66 into engagement with the teeth of the pinion 62 both members of the indicator are rotated together, but as the peripheral flanged portion 54 of the partial drum is moved before the sight opening 105 to display the desired digit thereon, the complete or inside drum is concealed from view.

In order that the teeth 67 of the segment gear 66 will engage with the teeth of the pinion 62 and not idly pass under the locking surface 68 of the cut away tooth when this segment gear is moved rearward, it is necessary slightly to move the partial drum as the inside drum moves past its "6" indicating position when a higher digit is to be indicated. To accomplish this purpose the free end of an arm 72 which is fastened to the inside drum by one of the pins 59, as best shown in Fig. 2, projects into the path of movement of the free end of an arm 71 which is fastened to the partial drum in a like manner. During rotation of the complete drum in a clockwise direction (Fig. 1) past its "6" indicating position the arm 72 engages the arm 71 just as the peripheral surface 69 of the segment gear 66 slides out of engagement with the locking surface 68 of the pinion 62 so that the partial drum and pinion 62 are slightly turned by the 130

movement of the complete drum, whereby the tooth 74 of the pinion 62 is brought into engagement with the foremost of the teeth 67. When the segment gears 47 and 66 are moved forward again to display a digit on the complete drum the teeth on the segment gear 66 rotate the partial drum until the locking surface 68 of the pinion 62 is again in locking engagement with the co-operating periphery 69 of the segment gear 66.

With the above described construction it can be seen that the principal object of the invention is accomplished by providing two drums 51 and 52, instead of a single drum, for one denomination series of digits. In this way the digits can be made much larger, and at the same time, as the diameter of the outside drum 52 is preferably not any larger than that of the single drums heretofore employed, the indicating mechanism of the present invention does not require more space in the machine.

For the purpose of alining the indicator drums in their proper indicating positions alining pawls 75, one for each drum, are provided. These pawls 75 have V-shaped notches 761 in their lower ends, the notches being designed to engage over the teeth on the pinions 60 and 62. The pawls 75 are rigidly mounted on a shaft 76, which also has rigidly mounted thereon a rearwardly projecting arm 77. A pitman 78 is pivotally connected to the outer end of the arm 77, and at its lower end is bifurcated to straddle a shaft 79. A roller 80 on the pitman projects into a cam groove 81 formed in the face of a disk 82, which is rigidly mounted on the shaft 79. The shaft 79 is given one complete rotation at each operation of the machine, and the shaft receives its rotation from the shaft 36 through the medium of the gear 83, fast on the shaft 79, the intermediate gear 85, and the gear 86 fast on the shaft 36, the pitch lines of these gears being indicated by dot-dash lines in Fig. 1. The form of driving mechanism and connections for the shafts 79 and 36 form no part of the present invention, and are, therefore, not shown in detail in the drawings. It is merely necessary to be understood that each of said shafts receives one complete rotation at each operation of the machine. The cam groove 81 is so designed that at the very beginning of the operation of the machine, the shaft 76 is rocked to raise the pawls out of engagement with the pinions 60 and 62. After the arms 27 have completed their upward movement, and before they begin their return movement to normal position, the cam 82 rocks the pawls 75 back to alining position. This is effected just at the time that the roller 50 is holding the curved portion of the link 41 against collar 411.

From the above description, it will be obvious that the present invention is adapted

for use in a printing mechanism and the like. With such a construction of the printing wheels larger characters could be printed without the necessity of making the printing wheels or drums any larger in diameter than the printing wheels or drums of an ordinary construction. It, therefore, is not intended to limit the use of the present invention to indicating mechanism as it is equally as well adapted for use in a printing mechanism and the like.

While the form of mechanism herein shown and described, is admirably adapted to fulfil the objects primarily stated, it is to be understood that it is not intended to confine the invention to the one form of embodiment herein shown and described, as it is susceptible of embodiment in various forms, all coming within the scope of the claims which follow.

What is claimed is:

1. In a machine of the class described, the combination with two accounting elements each bearing a part of the digits or characters of a series and so constructed that any digit or character on either element may be brought to a common effective point, and differential mechanism for operating the same.

2. In a machine of the class described, the combination with an accounting element bearing part of a series of digits or characters, of a second accounting element bearing the remaining digits or characters of the series, and differential mechanism for operating said accounting elements so that but one digit or character of the series is brought into effective position.

3. In a machine of the class described, the combination with an indicator element bearing part of a series of digits or characters, of a second indicator element bearing the remaining digits or characters of the series, and differential mechanism common to the two indicator elements for operating the same so that but one digit or character of the series is displayed at a time.

4. In a machine of the class described, the combination with two indicator elements each bearing a number of digits or characters of a series and so constructed that any digit or character on either element may be brought to a common reading point, and differential mechanism common to the two indicator elements for operating the same.

5. In a machine of the class described, the combination with two rotary indicator elements, one positioned within the other and each bearing a number of digits or characters of a series, and differential mechanism for rotating the indicator elements to bring any digit or character on either indicator element to a common reading point.

6. In a machine of the class described, the combination with a partial indicator drum

- bearing part of a series of digits or characters, of a second indicator drum bearing the remaining digits or characters of the series and positioned within the partial drum, two 5 actuators, one for each drum, and differential mechanism common to both actuators for operating the same to bring a digit or character on one or the other of said drums to indicating position.
16. 7. In a machine of the class described, the combination with an indicator drum bearing part of a series of digits or characters, of a second indicator drum bearing the remaining digits or characters of the series, actuating mechanism for the indicator drums so constructed that the first mentioned drum is not actuated when the digits or characters on the second drum are being displayed.
8. In a machine of the class described, the 20 combination with a partial indicator drum bearing part of a series of digits or characters, of a second indicator drum bearing the remaining digits or characters of the series and positioned to rotate within the partial 25 drum, and actuating mechanism for the indicator drums so constructed that the partial drum is not actuated when the second drum is displaying its digits or characters.
9. In a machine of the class described, the 30 combination with a partial indicator drum bearing part of a series of digits or characters, of a second drum bearing the remaining digits or characters of the series, and actuating mechanism for the indicator drums 35 constructed to lock the partial indicator drum against movement when the second drum is displaying its digits or characters.
10. In a machine of the class described, the combination with a partial indicator 40 drum bearing part of a series of digits or characters, of a second indicator drum bearing the remaining digits or characters of the series and positioned to move within the partial drum, and actuating mechanism for 45 the indicator drums and constructed to lock the partial indicator drum against movement when its digits or characters are not passing or in indicating position.
11. In a machine of the class described, the combination with a partial indicator 50 drum bearing part of a series of digits or characters, of a second indicator drum bearing the remaining digits or characters of the series, pinions rigidly connected to said 55 drums the pinion connected with the partial drum having a locking surface, and an actuating segment gear for each pinion, the actuating segment gear for the partial drum having a locking surface for coöperating 60 with the locking surface of the corresponding pinion when the partial indicator drum is out of indicating position.
12. In a machine of the class described, the combination with a partial indicator 65 drum bearing part of a series of digits or
- characters, of a second indicator drum bearing the remaining digits or characters of the series, pinions rigidly connected to said drums the pinion connected with the partial drum having a locking surface, and rigidly 70 connected actuating segment gears, one for each pinion, the actuating segment gear for the partial drum having locking surface for coöperating with the locking surface of its pinion when the partial drum is out of 75 indicating position.
13. In a machine of the class described, the combination with a partial indicator drum, bearing part of a series of digits or characters, of a second indicator drum bearing 80 the remaining digits or characters, pinions rigidly connected to said drums, the pinion connected to the partial drum having a cut away portion, an actuating segment gear for each pinion, the actuating segment 85 gear for the partial drum being provided with a locking surface for coöperating with the cut away portion of the pinion for the partial drum while the second drum is displaying its digits or characters, and means 90 for slightly moving the partial indicator drum as the second indicator passes its highest indicating position so that the actuating segment gear for the partial drum will engage the teeth on its corresponding 95 pinion.
14. In a machine of the class described, the combination with a differentially adjustable element, of a plurality of accounting elements each bearing characters representing a part of the positions of said adjustable element and movable to bring any desired character on any accounting element to a common position where the character will be effective, and operating connections 100 between the accounting elements and the differential element.
15. In a machine of the class described, the combination with a bank of keys, of a plurality of accounting elements each bearing characters representing a part of the keys and movable to bring any desired character on any element to a common position 105 where the character will be effective, and devices connected to the accounting elements and controlled by the keys for differentially operating the elements.
16. In a machine of the class described, the combination with a plurality of rotatable indicator elements each bearing a part 110 of the digits of a denominational order and movable to bring any desired digit to a reading point common to the elements, and differential mechanism common to the elements for operating the elements.
17. In a machine of the class described, the combination with two indicator elements each bearing a part of the digits of a denominational order and movable to bring any digit on either element to a position 115 120 125 130

common to the elements, of indicator actuating devices common to the elements and differentially movable directly and in either direction from one position to another, and 5 manipulative devices for controlling the direction and extent of movement of the actuating devices.

18. In a machine of the class described, the combination with two indicator elements 10 each bearing a part of the digits of a denominational order and adjustable to bring any digit on either element to a position common to the elements, of indicator actuating devices common to the elements and 15 differentially movable directly and in either direction from one position to another, and a series of keys for controlling the direction and extent of movement of the actuating devices.

20. 19. In a machine of the class described, the combination with a plurality of indicator elements each bearing a part of the digits of a denominational order and adjustable to bring any digit on either element to a position common to the elements, of indicator actuating segments common to the elements and movable as a unit directly and in either direction from one position to another, and manipulative devices for 25 controlling the direction and extent of movement of the segments.

20. In a machine of the class described, the combination with a plurality of indicator elements each having a part of the 30 digits of a denominational order and operable to display any desired character on any 35

element, of indicator actuating segments common to the elements and movable as a unit directly and in either direction from one position to another, and a series of keys 40 for controlling the direction and extent of movement of the segments.

21. In a machine of the class described, the combination with a plurality of rotatable indicator elements, of an actuating segment for each element, the segments being rigid together and arranged to start their elements at different points in the unitary movement of the segments, a differentially adjustable member, a beam 50 pivotally connected at one end to the actuating segments and at the other end to the differentially adjustable member, and means whereby a point intermediate the ends of the beam will be given a constant position 55 at each operation thereby effecting differential movement in either direction of the indicator actuating segments.

22. In a machine of the class described, the combination of a plurality of nested rotary indicators each bearing a part of the digits for a denominational order, of means 60 for operating the indicators to display any desired digit thereon at a point common to all of the digits, and manipulative devices 65 controlling said operating means.

In testimony whereof I affix my signature in the presence of two witnesses.

HAAKON A. MARTIN.
